[57] CLAIM

The ornamental design for a toothbrush holding device for a toothpaste canister, as shown and described.

DESCRIPTION

FIG. 1 is a perspective view of a toothbrush holding device for a toothpaste canister showing my new design therefor. The broken line drawings representing a toothpaste canister and a toothbrush are for purposes of illustration only and form no part of my design;

FIG. 2 is a top plan view;

FIG. 3 is a front elevational view, the rear elevational view being a mirror-image thereof;

FIG. 4 is a right side elevational view, the left side elevational view being a mirror-image thereof; and,

FIG. 5 is a bottom plan view.
